CONVERTIBLE ARTICLE OF FURNITURE

Warwick Mayo and Elbridge E. Nock, Jr., Norfolk,
Va., assignors to Norfolk Mattress Company,
Inc., Norfolk, Va.

Application December 16, 1935, Serial No. 54,754

13 Claims. (Cl. 5—44)

This invention relates to a convertible article of furniture and has for its object to provide, in a manner as hereinafter set forth, an article of the class referred to capable of being converted from a davenport into a twin bed.

A further object of the invention is to provide, in a manner as hereinafter set forth, a foldable and extendible structure having the elements thereof so formed and arranged relative to each other to enable the structure to be selectively used as a davenport or bed when desired.

A further object of the invention is to provide, in a manner as hereinafter set forth, a foldable and extendible structure having as parts thereof a cushioned element constituting the bottom of a davenport and a bed bottom for one of a pair of beds of the twin bed type and an extendible cushion element functioning, when in non-extended position, as the back of a davenport and when in extended position as the bed bottom of the other bed of a pair of beds of the twin bed type.

Further objects of the invention are to provide, in a manner as hereinafter set forth, a foldable and extendible article of furniture for the purpose referred to which is simple in its construction and arrangement, strong, durable, compact, pleasing in appearance when in non-extended position, conveniently extended and folded when occasion so requires and comparatively inexpensive to manufacture with respect to articles of the class to which this invention belongs.

With the foregoing and other objects which may hereinafter appear, the invention consists of the novel construction, combination and arrangement of parts as will be specifically described and are as illustrated in the accompanying drawings wherein is shown the preferred embodiment of the invention, but it is to be understood that changes, variations and modifications may be resorted to which fall within the scope of the invention as claimed.

In the drawings:

Figure 1 is a fragmentary view in top plan of the article of furniture converted into a twin bed.

Figure 2 is an end elevation of the article of furniture converted into a davenport.

Figure 3 is a vertical section of the article of furniture when converted into a twin bed.

Figure 4 is a vertical section of the article of furniture when converted into a davenport.

Figure 5 is a fragmentary view in perspective of the frame work of the article of furniture.

Figure 6 is a section on line 6—6, Figure 5.

Figure 7 is a fragmentary view in perspective illustrating the frame work of the normally housed section of the article of furniture.

Figure 8 is a section on line 8—8, Figure 7.

Figure 9 is a detail in section illustrating the fastening arrangement for the lower end of a side arm element, and

Figure 10 is a fragmentary view in section illustrating the fastening arrangement for the upper end of a side arm element.

The article of furniture includes a shiftable section 12 consisting of a rectangular supporting frame 13 formed of an angle-shaped front member 14 having a vertical and a horizontal leg 15, 16 respectively and with the leg 16 extending rearwardly from the upper end of the leg 15, a pair of inverted yoke-shaped vertically disposed side members 17, 18, each including a top 19 and front and rear legs 20, 21 respectively of angle-shaped cross section, a rear frame member 22 of angle-shaped cross section formed of a horizontal leg 23 and a vertical leg 24 which merges at its lower end into the rear side of leg 23 and spaced transversely extending parallel brace members 24a. The horizontal leg 16 of the member 14 is mounted upon the ends of the top 19 of the yokes 17, 18. The vertical leg 15 of the member 14 is positioned against the forward ends of the tops of the side members 17, 18. The horizontal leg 23 of the member 22 is positioned upon the upper face of the tops of the members 17, 18 at the rearward ends of the latter. The brace members 24a are positioned against the lower faces of the legs 16 and 23 of the members 14 and 22. The members 14, 17, 18, 22 and braces 24a are suitably secured together. Secured to the lower faces of the tops of the side members 17, 18 are spaced parallel cushioning wires 25. Secured to the lower face of the legs 16, 23 of the members 14, 22 respectively are transversely extending parallel spaced cushioning wires 26. The wires 25 and 26 are interwoven and are arranged above the braces 24a.

The rear legs 21 of the members 17, 18 are provided with a vertical cutout, as indicated at 26. Secured to the front and rear legs 20, 21 respectively of the members 17, 18 and below the cutouts 26 are transversely disposed combined brace and supporting members 27 of angle-shaped cross section. The members 27 are arranged below the braces 24a. Each member 27, in proximity to a rear leg 21, is formed with a lengthwise extending slot 28. Secured upon the upper face of each member 27 is a slidable coupler 29. Fixed to the upper face of each member 24 and arranged

opposite member 29 is a stationary coupler 30. The coupler 29 is arranged over the slot 28 and is slideable relative to that member 27 upon which it is mounted. Interposed between the couplers 29, 30 and having its ends anchored to the upper ends of the said couplers is a coiled controlling spring 31. Extending through the lower end of the coupler 29 is a connecting pin 32 which passes through the slot 28 and is attached to a vertically disposed angle-shaped retarder 33 for a purpose to be referred to. The retarder 33 bodily shifts with the coupler 29 when the retarder 33 is moved rearwardly by a means to be referred to. The retarder 33, in connection with the pin 32, coupler 15 29, spring 31 and coupler 30, forms a cushioning means for a purpose to be referred to. The front and rear legs 20, 21 respectively of the members 17, 18 are provided with casters 34 at their lower ends.

20 Positioned upon the wires 24, 25 is a cushioning structure 35 of the coiled spring type. Mounted upon and surrounding the structure 35 is a padding 36 which seats upon side supports 37, a front support 38 and a rear support 39. The supports 37 and 38 are arranged at the sides and front of the frame 13. The support 39 extends above the rear of the frame 13. The supports 37 and 38 are of greater width than the support 39. The supports 37, 38 and 39 are secured to the frame 13. The supports 37 and 38 have their bottom edges arranged slightly above the members 31. Secured to the outer face of supports 37, 38 and 39 and enclosing the padding 36 is a facing 40 of any suitable fabric.

35 The structure 35, padding 36 and facing 40 constitute the bottom of a davenport or a bed bottom and which is supported by the frame 13.

The article includes an adjustable combined davenport back and bed bottom element 41 comprising a rectangular frame 42 of less length and of substantially the same width as the supporting frame 13. The body of frame 42 throughout is of angle-shape in transverse cross section thereby providing its front, sides and rear with inner and outer legs 43, 44 disposed at right angles to each other. Connected to the legs 43 of the sides of the frame is a rectangular resilient skeleton member 45. Secured against the inner faces of the legs 43 and 44 of the front and rear of the frame and flush with the free edges of said legs are wooden strips 46 which are arranged in parallel spaced relation. The frame 42 is completely encased by a fabric covering 47 which is suitably secured to the wooden strips 46. The front side 50 of casing 47 has connected thereto spaced grommets 48 having their inner faces registering with spaced threaded openings 49 formed in the legs 44 of the front of the frame 42.

The article includes a supporting structure 51 for element 41 when the latter is in davenport back and bed bottom forming positions. The structure 51 is adapted to be normally housed within and to extend rearwardly from the frame 13 when the structure 12 is shifted forwardly relative to the structure 51. When the structure 51 is housed in the section 12 the article of furniture will be in the form of a davenport. When the structure 51 extends rearwardly from the frame 13 the article of furniture will be in the form of twin beds. The structure 51 functions to support the element 41 horizontally when the article of furniture is in the form of twin beds and functions to support the element 41 in an upstanding position to provide the back of a 70 davenport when the article of furniture is con-

verted into a davenport. The structure 51 is slidably connected to the braces 27 of the frame 13 and the connection is such to provide a cushioning action at the extent of the forward shift of section 12 relative to structure 51. The structure 51 comprises a rectangular frame 52 supported on front and rear vertical legs 53, 54 respectively provided with foot pieces 55. Bracing members 66 connect the legs 53, 54 to the frame 52. Extending forwardly from each side of the frame 52 is an angle-shaped arm 67 formed with an outwardly directed leg 68. The retarder 33 includes a horizontal leg 69 and a vertically disposed leg 70. The legs 70 of the retarders 33 are disposed in the path of the legs 68 of the arms 15 67. The front and rear members 71, 72 respectively of the frame 52 seat upon the end members 73 of frame 52. Anchored upon and secured to each end member 73, as at 74, as well as extending upon rear member 72 is an angle iron 75 20 formed of a horizontal leg 76 and a vertical leg 77. The angle iron 75 is also secured to end member 73, as at 78. The means which anchors the angle iron 75 to the legs 72 and 73 extends through the horizontal leg 76 of the iron 75. The 25 leg 77 of angle iron 75 opposes in spaced relation the inner face of the inner portion of the leg 44 of the frame 42. The leg 77 of angle iron 75 has interposed therebetween and inner portion of leg 44, spacing collars 79. Extending through the 30 leg 77 of angle iron 75 and leg 44 of frame 42, as well as the spacing collar 79, is a pivot 80. The pivots 80 pivotally connect the element 41 to the rear of the structure 51. The pivots 80 are arranged in proximity to the ends of the inner portion of the leg 44 of the frame 42. The cover 47, which forms a part of element 41, is formed in a suitable manner, as indicated at 81, to provide clearances for the angle iron 75 when the element 51 is in the position shown in Figures 40 3 and 4. The element 41 folds forwardly relative to structure 51 to provide the davenport back and downwardly to provide the bed bottom.

The article includes a pair of arm rest elements 82 of like form and of angle-shaped contour. Each element 82 has an arm rest 83 secured thereto. Each element 82 is formed with a vertically disposed forward arm 84 and a horizontally disposed rearwardly extending arm 85. The forward arm 84 of each element 82 is pivotally connected at its lower end with and in spaced relation relative to a side of frame 13 and in the manner as shown in Figure 9. The leg 24 has an opening 86 through which extends a pivot bolt 87 formed with a reduced inner threaded end 88 which, in connection with the remaining portion of the bolt 87, provides the latter with a peripheral shoulder 89. Mounted on the bolt 87 is a spacing collar 90 which abuts against the grommet 91 formed in the facing 40. The reduced portion 60 88 of the bolt 87 extends through the grommet 91 and an opening 92 formed in a support 37. The frame 13, at each side, is formed with a threaded opening 93 and each of which aligns with an opening 92. The reduced end 88 of bolt 65 87 threadedly engages with the wall of the opening 93. The horizontal arm 85 of each element 82 has its rear end provided with a depending lug 94 formed with an opening 95. Extending through the opening 95 is a pivot bolt 96 having 70 a reduced threaded inner portion 97 which extends through the grommets 48 and threadedly engages with the wall of the opening 49.

The article of furniture includes a cushion or mattress 98 which, when the article is in the form 75

5 of a davenport, provides the removable seat therefor and when the article is in the form of a twin bed is employed to provide the mattress for the latter in a manner as is shown in Figure 3. The height of the cushion 98 is such that when the article is converted into a twin bed and cushion 98 used as a mattress for one of the beds, it will be flush with the upper face of the non-extensible section 12.

10 It will be assumed that the article of furniture is in the form of a davenport, such as that shown in Figure 4, and it is desired to convert it into a twin bed. The structure 12 is shifted forwardly, which by exerting a forward pull on 15 pivot 81 through arm rests 82 causes the back forming element 4 to move forwardly and downwardly on the pivots 80 until the element 41 assumes the position shown in Figure 3 mounted upon and extended rearwardly from the structure 51. As the structure 12 is shifted forwardly, the structure 51 extends rearwardly from the section 12. As the structure 51 is extended rearwardly from the section 12 the legs 68 will coact with the legs 70 whereby the springs 31 will be 20 expanded to set up a cushioning action. When the structure 51 and element 41 are in the position shown in Figure 3 they will hold the springs 31 expanded. After the element 41 and structure 51 are in the position shown in Figure 3 the 25 cushion 98 is mounted thereon. When it is desired to convert the structure from a twin bed into a davenport, cushion 98 is removed from element 41, the front edge of the back structure is then released from engagement with the rear of 30 the seat and the housing section 12 is then free to run back over section 1 to the position shown in Figure 4 to form a davenport. After the element 41, elements 82 and structure 51 have assumed the position shown in Figure 4 the cushion 40 98 is mounted upon the section 12.

The article of furniture, if desired, may have as parts thereof removable pillows, as indicated at 99.

45 The section 12 is a davenport body forming section and will be termed in the claims as a shiftable housing structure as it functions as a housing for the stationary supporting structure 51 when the latter is not arranged to horizontally support, in superimposed relation thereto, 50 the element 41. The elements 82 also function as means for retaining the element 41 in an upstanding position when the latter functions as a back for the davenport or divan. The element 41 has secured thereto a pair of spaced annular aligning 55 lifting members 100.

What we claim is:

1. A convertible article of furniture comprising a shiftable housing structure in the form of a davenport body, a pair of arm rests, a supporting 60 structure normally housed within and extending rearwardly with respect to said housing structure when the latter is shifted forwardly relative to the supporting structure to provide a support for a bed bottom, a forwardly foldable combined davenport back and bed bottom forming element normally disposed in upstanding position at the rear of said housing structure, when the article is 65 assembled, to provide a davenport back, and forwardly foldable from upstanding position to horizontal position in superimposed relation upon said supporting structure when the latter extends rearwardly relative to said housing structure to provide a bed bottom, means pivotally connecting the forward ends of said arm rests to the sides 70 of said housing structure, means pivotally connecting the rear ends of said arm rests to the sides of said element, means pivotally connecting said element to said supporting structure, the rear ends of said arm rests being provided with angularly disposed extensions, and the means connecting the rear ends of said arms to said element passing through said extensions. 5

2. A convertible article of furniture comprising a shiftable housing structure constituting a davenport body and having a part thereof forming a spring bed bottom, a supporting structure normally housed within and extending rearwardly with respect to said housing structure when the housing structure is shifted forwardly relative thereto to provide a support for a bed bottom, a forwardly foldable combined davenport back and spring bed bottom forming element for selectively arranging in an upstanding position at the back of said housing structure to constitute a davenport back and in a horizontal position in superimposed relation upon said supporting structure when the latter is extended to provide a bed bottom, a pair of arm rests pivoted to said housing structure and to said element, and means pivotally connecting the rear of said element to said supporting structure. 10

3. A convertible article of furniture comprising a shiftable housing structure constituting a davenport body and having a part thereof forming a spring bed bottom, a supporting structure normally housed within and extending rearwardly with respect to said housing structure when the housing structure is shifted forwardly relative thereto to provide a support for a bed bottom, a forwardly foldable combined davenport back and spring bed bottom forming element for selectively arranging in an upstanding position at the back of said housing structure to constitute a davenport back and in a horizontal position in superimposed relation upon said supporting structure when the latter is extended to provide a bed bottom, a pair of arm rests pivoted to said housing structure and to said element, and means pivotally connecting the rear of said element to said supporting structure. 15

30 4. A convertible article of furniture comprising a shiftable housing structure constituting a davenport body and having a part thereof forming a spring bed bottom, a supporting structure normally housed within and extending rearwardly with respect to said housing structure when the housing structure is shifted forwardly relative thereto to provide a support for a bed bottom, a forwardly foldable combined davenport back and spring bed bottom forming element for selectively arranging in an upstanding position at the back of said housing structure to constitute a davenport back and in a horizontal position in superimposed relation upon said supporting structure when the latter is extended to provide a bed bottom, a pair of arm rests pivoted to said housing structure and to said element, means pivotally connecting the rear of said element to said supporting structure, and said supporting structure having coacting means for cushioning the housing structure on the forward shifting thereof and for assisting the return of the housing structure to housing position relative to the supporting structure. 35

40 5. A convertible article of furniture comprising a slidably supported spring controlled shiftable housing structure constituting a davenport body and having a part thereof forming a spring bed bottom, a supporting structure normally housed within said housing structure below said spring bottom and extending rearwardly with respect to said housing structure to provide a support for a bed bottom when the housing structure is shifted from complete housing position relative to the 45 said supporting structure, said structure having coacting means to prevent their separation when the housing structure is shifted relative to the supporting structure, a rectangular forwardly foldable combined davenport back and spring bottom forming element for selectively arranging in an upstanding position at the back of the said housing structure to constitute a davenport back and in a horizontal position in superposed relation upon said supporting structure, when the latter extends rearwardly of the housing structure, to provide a bed bottom, a pair of upstanding angle-shape arm rests pivoted at their forward ends to said housing structure and at their rear ends to said element, and means pivotally 50

55 6. A convertible article of furniture comprising a shiftable housing structure constituting a davenport body and having a part thereof forming a spring bed bottom, a supporting structure normally housed within said housing structure below said spring bottom and extending rearwardly with respect to said housing structure to provide a support for a bed bottom when the housing structure is shifted from complete housing position relative to the 60 said supporting structure, said structure having coacting means to prevent their separation when the housing structure is shifted relative to the supporting structure, a rectangular forwardly foldable combined davenport back and spring bottom forming element for selectively arranging in an upstanding position at the back of the said housing structure to constitute a davenport back and in a horizontal position in superposed relation upon said supporting structure, when the latter extends rearwardly of the housing structure, to provide a bed bottom, a pair of upstanding angle-shape arm rests pivoted at their forward ends to said housing structure and at their rear ends to said element, and means pivotally 65

70 7. A convertible article of furniture comprising a shiftable housing structure constituting a davenport body and having a part thereof forming a spring bed bottom, a supporting structure normally housed within said housing structure below said spring bottom and extending rearwardly with respect to said housing structure to provide a support for a bed bottom when the housing structure is shifted from complete housing position relative to the 75 said supporting structure, said structure having coacting means to prevent their separation when the housing structure is shifted relative to the supporting structure, a rectangular forwardly foldable combined davenport back and spring bottom forming element for selectively arranging in an upstanding position at the back of the said housing structure to constitute a davenport back and in a horizontal position in superposed relation upon said supporting structure, when the latter extends rearwardly of the housing structure, to provide a bed bottom, a pair of upstanding angle-shape arm rests pivoted at their forward ends to said housing structure and at their rear ends to said element, and means pivotally 75

connecting said element to the rear of said supporting structure, the pivot connections between the rear ends of said arm rests and said element and the pivot connections between said element and supporting structure being spaced from each other.

5. In a convertible article of furniture a shiftable combined davenport body and bed bottom forming structure having its lower portion including a frame provided with spaced roller supports, a stationary bed bottom supporting structure normally housed in the said lower portion and extended from the latter when the shiftable structure is moved to non-housing position relative to said stationary structure, a forwardly foldable combined davenport back and bed bottom forming element normally disposed vertically in abutting relation with the rear of the shiftable structure, when the article is assembled, to form a davenport back and foldable forwardly from vertical to horizontal position in superimposed relation with respect to the stationary section, when the latter is extended, to constitute a bed bottom, said supporting structure and element having co-acting means for supporting said element vertically and for permanently pivotally connecting said element to said supporting structure, and a pair of arm rests, each having one end pivotally connected to said shiftable structure and its other end to said element.

6. In a convertible article of furniture a shiftable combined davenport body and bed bottom forming structure having its lower portion including a frame provided with spaced supporting legs carrying rollers, a stationary bed bottom supporting structure normally housed in the said lower portion and extended from the latter when the shiftable structure is moved to non-housing position relative to said stationary structure, a forwardly foldable combined davenport back and bed bottom forming element, normally disposed vertically in abutting relation with the rear of the shiftable structure, when the article is assembled, to form a davenport back and foldable forwardly from vertical to horizontal position in superimposed relation with respect to the stationary section, when the latter is extended to constitute a bed bottom, said supporting structure and element having co-acting means for supporting said element vertically and for permanently pivotally connecting said element to said supporting structure, and a pair of arm rests, each having one end pivotally connected to said shiftable structure and its other end to said element, said shiftable structure having the said lower portion thereof provided with supports carrying resilient devices having means engageable by the supporting structure, when the shiftable structure is moved from non-housing position to cushion the latter and to assist in the returning of the shiftable structure to housing position when said element is shifted from bed bottom forming position.

7. In a convertible article of furniture, a shiftable structure, a stationary supporting structure normally housed in the lower portion of and extended from the rear of the shiftable structure when the latter is moved to non-housing position, a forwardly foldable rectangular element, disposed vertically on one of its lengthwise edges relative to the back of said shiftable structure, when the article is assembled and disposed horizontally relative to the top of the supporting structure when the latter is extended, said element and supporting structure carrying co-acting means for supporting said element when the latter is

vertically disposed and for permanently pivotally connecting it to the supporting structure, the said co-acting means carried by the supporting structure being at the rear of the sides of the latter, the co-acting means carried by said element being in proximity to the rear ends of the sides of the latter, and a pair of arm rests, each having one end pivoted to the lower portion of the shiftable structure and its other end pivoted to a side of said element.

8. In a convertible article of furniture, a shiftable structure, a stationary supporting structure normally housed in the lower portion of and extended from the rear of the shiftable structure when the latter is moved to non-housing position, a forwardly foldable rectangular element disposed vertically on one of its lengthwise edges relative to the back of said shiftable structure, when the article is assembled and disposed horizontally relative to the top of the supporting structure when the latter is extended, said element and supporting structure carrying co-acting means for supporting said element when the latter is vertically disposed and for permanently pivotally connecting it to the supporting structure, the said co-acting means carried by the supporting structure being at the rear of the sides of the latter, the co-acting means carried by said element being in proximity to the rear ends of the sides of the latter, and a pair of arm rests, each pivoted at one end to said shiftable structure and at its other end to said element.

9. A convertible article of furniture comprising a shiftable housing structure in the form of a davenport body, a pair of arm rests, a supporting structure normally housed within and extended rearwardly from said housing structure to provide a support for a bed bottom when the housing structure is shifted forwardly relative to the supporting structure, a foldable combined davenport back and bed bottom forming element unfolding upwardly and rearwardly to an upstanding position at the rear of said housing structure when the article is assembled to provide a davenport back and foldable forwardly to a horizontal position in superimposed relation with respect to said supporting structure to provide a bed bottom when the supporting structure is extended, means pivotally connecting the forward ends of said arm rests to the sides of said housing structure, means pivotally connecting the rear ends of said arm rests to the sides of said element, and means pivotally connecting said element to said supporting structure.

10. A convertible article of furniture comprising a shiftable housing structure in the form of a davenport body, a pair of angle-shaped arm rests, a supporting structure normally housed within and extended rearwardly from said housing structure to provide a support for a bed bottom when the housing structure is shifted forwardly relative to the supporting structure, a foldable combined davenport back and bed bottom forming element unfolding upwardly and rearwardly to an upstanding position at the rear of said housing structure when the article is assembled to provide a davenport back and foldable forwardly to a horizontal position in superimposed relation with respect to said supporting structure to provide a bed bottom when the supporting structure is extended, means pivotally connecting the forward ends of said arm rests to the sides of said housing structure, means pivotally connecting the rear ends of said arm rests to the sides of said element, means pivotally

connecting said element to said supporting structure, said supporting structure being formed at its front with oppositely disposed stop arms, said housing structure being provided therein with expandable and contractible devices disposed for engagement by said stop arms to impart a cushioning action to said housing structure when the latter is shifted forwardly relative to said supporting structure and for assisting the return of 10 said housing structure to housing position relative to said supporting structure.

11. A convertible article of furniture comprising a shiftable housing structure in the form of a davenport body, a pair of angle-shaped arm rests, a supporting structure normally housed within and extended rearwardly from said housing structure to provide a support for a bed bottom when the housing structure is shifted forwardly relative to the supporting structure, a 20 foldable combined davenport back and bed bottom forming element unfolding upwardly and rearwardly to an upstanding position at the rear of said housing structure when the article is assembled to provide a davenport back and foldable forwardly to a horizontal position in superimposed relation with respect to said supporting structure to provide a bed bottom when the supporting structure is extended, means pivotally connecting the forward ends of said arm rests 25 to the sides of said housing structure, means pivotally connecting the rear ends of said arm rests to the sides of said element, means pivotally connecting said element to said supporting structure, said supporting structure being formed at 30 its front with oppositely disposed stop arms, said housing structure being provided therein with expandable and contractible devices disposed for engagement by said stop arms to impart a cushioning action to said housing structure when the latter is shifted forwardly relative to said supporting structure and for assisting the return of 35 said housing structure to housing position relative to said supporting structure, and spacing means between the forward ends of said arm rests 40 and said housing structure and between the rear ends of said arm rests and said element.

12. A convertible article of furniture comprising a shiftable housing structure in the form of a davenport body, a pair of arm rests, a supporting structure normally housed within and extend-

ed rearwardly with respect to said housing structure when the latter is shifted forwardly relative to the supporting structure to provide a support for a bed bottom, a foldable combined davenport back and bed bottom forming element unfolding upwardly and rearwardly to upstanding position at the rear of said housing structure to provide a davenport when the article is assembled and foldable forwardly to a horizontal position in superimposed relation with respect to said supporting structure to provide a bed bottom when the supporting structure is extended rearwardly from the housing structure, means pivotally connecting said arm rests to the sides of said housing structure, means pivotally connecting said element to said supporting structure, said supporting structure having at its front oppositely disposed stop arms, said housing structure being provided therein with expandable and contractible devices disposed to be engaged by said stop arms imparting a cushioning action to said supporting structure when extended rearwardly relative to the housing structure and for assisting the return of the housing structure to housing position relative to said supporting structure, said 20 arm rests being provided with angularly disposed extensions, and means pivotally connecting the extensions of said arm rests to said element.

13. In an extension couch the combination of a pair of relatively movable seat and bed members, one of which is adapted to receive and house the other or be situated in extended position at one side of the other, a back rest member pivotally attached to the rear of one of said relatively movable members, and adapted to turn forward to horizontal position and means pivotally connecting the back rest member and the other of said relatively movable members, said means comprising a substantially rigid arm rest pivoted at one end on said back rest member at a point removed from its pivotal attachment and at the other on said other member whereby operation of the back rest upon its pivotal attachment to the one of said relatively movable members will effect movement of the relatively movable seat and bed members to extended position or to housed relation.

WARWICK MAYO.
ELBRIDGE E. NOCK, JR. 50
